LAMP

Paul H. Irmischer, Chicago, Ill.

Application May 20, 1952, Serial No. 19,797

Term of patent 3½ years

(Cl. D48—20)

To all whom it may concern:

Be it known that I, Paul H. Irmischer, a citizen of the United States, and a resident of Chicago, in the county of Cook, and State of Illinois, have invented a new, original, and ornamental Design for a Lamp, of which the following is a specification, reference being had to the accompanying drawings, forming a part thereof, and in which:

Fig. 1 is a perspective view of a lamp, showing my new design;

Fig. 2 is a perspective view thereof, viewed from the side opposite to that shown in Fig. 1.

I claim:

The ornamental design for a lamp, as shown.
PAUL H. IRMISCHER.
